CLAIM

The ornamental design for a fixture for assembling a solar module assembly, as shown and described.

DESCRIPTION

FIG. 1 is a perspective view of a fixture for assembling a solar module assembly showing our new design;

FIG. 2 is a top plan view thereof;

FIG. 3 is a front view thereof;

FIG. 4 is a side view thereof; and,

FIG. 5 is a bottom plan view thereof.

The broken lines shown represent unclaimed subject matter and form no part of the claimed design.
